(57) CLAIM

The ornamental design for a railroad tie souvenir, as shown and described.

DESCRIPTION

FIG. 1 is an upper perspective view of a railroad tie souvenir showing my new design comprised of a section of a wooden railroad tie within a support stand.

FIG. 2 is a front view of a railroad tie souvenir showing my new design.

FIG. 3 is a rear view of a railroad tie souvenir showing my new design.

FIG. 4 is a left side view of a railroad tie souvenir showing my new design.

FIG. 5 is a right side view of a railroad tie souvenir showing my new design.

FIG. 6 is a top view of a railroad tie souvenir showing my new design; and,

FIG. 7 is a bottom view of a railroad tie souvenir showing my new design.

Any shading and cross-hatching are not features of the design but are utilized to illustrate the surface contours and wood grain of the railroad tie souvenir in the drawings.
